US0D1081232S

(12) United States Design Patent (10) Patent No.: US D1,081,232 S
(45) Date of Patent: * Jul. 1, 2025

(54) DRINK MAKER

- (71) Applicant: SharkNinja Operating LLC,
Needham, MA (US)
- (72) Inventors: Cameron John Auger, Watertown, MA
(US); Joyce Chien Tu, Melrose, MA
(US)

- (73) Assignee: SharkNinja Operating LLC,
Needham, MA (US)

() Term: 15 Years

(21) Appl. No.: 29/975,344

(22) Filed: Nov. 27, 2024

Related U.S. Application Data

(63) Continuation of application No. 29/943,526, filed on May 22, 2024, which is a continuation-in-part of application No. 18/415,817, filed on Jan. 18, 2024.

(51) LOC (15) Cl. 07-01

(52) U.S. Cl. D7/311

(57) CLAIM

The ornamental design for a drink maker, as shown and described.

DESCRIPTION

FIG. 1 is a top front perspective view of a drink maker showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the drink maker that form no part of the claimed design.

1 Claim, 5 Drawing Sheets
